INVENTOR

John J. Fink

BY *Henry J. Webster*
ATTORNEY

UNITED STATES PATENT OFFICE.

JOHN J. FINK, OF LODI, CALIFORNIA.

INVISIBLE SUSPENDERS.

Application filed August 19, 1924. Serial No. 732,902.

To all whom it may concern:

Be it known that I, JOHN J. FINK, a citizen of the United States, residing at Lodi, county of San Joaquin, State of California, 5 have invented certain new and useful Improvements in Invisible Suspenders; and I do declare the following to be a full, clear, and exact description of the same, reference being had to the accompanying drawings, 10 and to the characters of reference marked thereon, which form a part of this application.

This invention relates to improvements in suspenders for men and boys, and particularly to a type especially intended to be worn under the shirt of the wearer, and to be attached to the ordinary trouser buttons through and in connection with the shirt.

The principal object of my invention is 20 to provide suspenders for the above named purpose so constructed that the trousers will be supported at substantially evenly spaced points about the waist line, thereby preventing an unsightly sagging of the trousers at 25 front or back.

A further object is to arrange the suspenders so that when disconnected from the trousers, they will not tend to slip down the back of the wearer as do suspenders of 30 the ordinary form. My suspenders are also so arranged that perfect ease of movement of the body of the wearer may be had, and in a short time he will be unconscious of the presence of the suspenders. My device is 35 also very easily attached or detached, without any contortions on the part of the wearer while doing so being necessary.

While my suspenders are particularly intended for use under the shirt, they may be 40 used outside the same if desired, and without any change being required.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views.

Fig. 1 is a perspective view of my sus-

penders as in service, and applied to a man and his garments.

Fig. 2 is a side view of one of the button-connecting units of the suspenders.

Fig. 3 is a fragmentary section of a trousers and shirt, showing one of the suspender fasteners in connection with the garments and a trousers button.

Referring now more particularly to the characters of reference on the drawings, the numerals 1 and 2 denote the main straps of the suspenders, of any suitable material, and crossed intermediate their ends. The crossing portions may be rigidly fixed together, or may have limited sliding movement relative to each other, as may be desired. Suitable lengthening and shortening means for 70 the straps, of any suitable character, is also provided as is customary.

The straps pass over and are supported from the shoulders of the wearer, the crossed portions being at the back.

The front portions of the straps 1 and 2 depend substantially parallel to each other to the sides of the chest of the wearer, the rear portion of the strap 1 terminating at the back of the wearer in substantial fore and aft alinement with the lower end of the front portion of the strap 2, while the rear portion of the strap 2 is correspondingly disposed relative to the front end of the strap 1.

Hook members 3 are fastened to and depend from the lower ends of the straps, the hooks on each corresponding pair of strap ends having a slidable connection with an endless loop 4 of flexible cord or the like, 90 said loop depending from the hooks.

A flexible piece of tape 5 or the like connects the upper and lower runs of the loop 4 between the hooks 3, making the loop assume an oblong form in a horizontal plane, and limiting the horizontal movement of the loop along the hooks. Fixed on and depending from the loop 4 beyond the connection 5 are loop-fasteners 6 of suitable form, of a type adapted to detachably engage the buttons 7 of a trousers 8, and to also enable the shirt 9 to be folded about the buttons and secured thereto by said fasteners.

It will therefore be seen that four button-fastening means are provided, and the trousers are therefore supported at four points.

Each pair of fasteners 6 is so spaced that the four points of support are practically evenly spaced about the top of the trousers, and the buttons, if not already so, are preferably relocated so that they also are evenly spaced about the trousers in alignment with the positions of the fasteners when the latter are hanging free.

In operation, with the straps disposed on the body of the wearer as previously set forth, it will be seen that the loops pass about the sides of the wearer a certain distance below and substantially in vertical alignment with the arm pits. Therefore even if the fasteners 6 are disconnected from the buttons, the straps cannot slide very far down the back of the wearer since such movement would be limited by the loops coming in contact with the arm-pits of the wearer. Even if such a position of the suspenders should be had, the forward fasteners 6 would still be within easy reach of the wearer.

The ends of the straps being diagonally and oppositely disposed relative to each other, and the different hooks 3 having slideable connection with the flexible loops 4, the strain on the trousers is equally distributed and counter-balanced, and the wearer may bend one way or the other with perfect freedom, and without any uneven pulling strain being placed on the suspenders or buttons at any point.

It is to be noted that I do not make any claim to the form of straps, hooks or fasteners in themselves, but to the arrangement of these parts in such a manner that the above recited advantages are obtained.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A suspenders including a pair of straps crossing each other intermediate their ends, hooks depending from the ends of the straps, flexible endless loops disposed in a vertical plane and slidably supported at spaced points on their upper runs by the adjacent hooks of opposite straps, a connection secured to and extending between the upper and lower runs of each loop between the hooks, whereby to prevent approach of the straps together and hold the upper and lower runs of the loop between the members in definitely spaced relation, and button engaging members depending from said lower runs only on both sides of the connection.

2. A suspenders including a pair of straps crossing each other intermediate their ends, hooks depending from the ends of the straps, flexible endless loops disposed in a vertical plane and only on the upper runs of which the adjacent hooks of opposite straps are slidably supported, and a pair of button engaging members fixed in spaced relation only on the lower run of each loop substantially in normal vertical alignment with the corresponding hooks; said lower run extending substantially horizontally between the button engaging members to form a direct connection therebetween.

3. A suspenders including a pair of straps crossing each other intermediate their ends, hooks depending from the ends of the straps, flexible endless loops disposed in a vertical plane and slidably supported by the adjacent hooks of opposite straps, and a pair of button engaging members fixed on the lower run of each loop, and means between the upper and lower run of the loop for preventing the strap-hooks on the loop from tending to approach close to each other when a vertical tension is exerted on the button engaging members, the hooks having sliding engagement only with the upper runs of the loops.

In testimony whereof I affix my signature.

JOHN J. FINK.
